UNITED STATES PATENT OFFICE.

NORRIS H. PAXSON, OF NEWPORT NEWS, VIRGINIA.

NUTMEG GRATER.

Application filed February 21, 1925. Serial No. 10,909.

To all whom it may concern:

Be it known that I, NORRIS H. PAXSON, a citizen of the United States, residing at Newport News, in the county of Warwick 5 and State of Virginia, have invented certain new and useful Improvements in Nutmeg Graters, of which the following is a specification.

The object of my invention is to provide 10 a nutmeg grater of such construction that it may be sold at a very low price.

Another object of my invention is to form the stem or handle and a housing for a grater from one piece of metal thereby 15 eliminating manufacturing steps incident to the joining of several pieces in one structure.

Another object of my invention is to provide in a continuous piece spokes, journals, 20 and an operating crank for the grater; and with these and other objects in view my invention consists of the parts and combination of parts as will be hereinafter more fully set forth.

25 In the drawings:

Figure 1 is a view of the blank flattened out from which the stem and grater housing are integrally formed.

Figure 2 is a front elevation of my im- 30 proved nutmeg grater.

Figure 3 is a vertical sectional view on the line 3—3, Figure 2.

Figure 4 is a longitudinal sectional view 35 of a grater with its spokes and journals in elevation.

Figure 5 is an end elevation of the grater.

The stem or handle designated by the reference numeral 1 is hollow and, preferably, 40 cylindrical and open at both ends, one end being closed by a block 2 which is held in position by means of the tag or similar device 3. A follower 4 is slidably mounted within the handle 1 and is provided in its lower face with a recess 5 within which one 45 end of a coil spring 6 is seated, the other end of the spring being seated on the block 2. The upper end of the follower is concaved and is covered with a roughened plate 7. The stem 1 is provided with elongated ver- 50 tically disposed slots 8 and 9 in which the end portions of the bar 10 are adapted to reciprocate, said bar being secured to the follower 4 whereby the follower may be moved downwardly against the tension of 55 the spring 8 for the purpose of inserting a nutmeg 11 through the opening 12 in one

wall of the stem 1. The opening 12 is in line with the elongated slot 8 as will be seen in Figure 2.

A vertical arm 13 is integral with and 60 extends upwardly from the stem 1 and has its upper end portion 14 bent inwardly at substantially right angles. Arms 15 and 16 are integral with and extend upwardly from the stem 1 and have their inner ends 17 65 and 18 bent inwardly so that the inwardly bent portions of the arms 13, 15 and 16 meet and are joined together by a single rivet 18, as shown in Figure 3, whereby these arms 13, 15 and 16 constitute a 70 housing for the grater and require but a single rivet to hold the housing in its formation. The arms 15 and 16 are provided with journal bearings which will be hereinafter referred to.

The grater is designated by reference numeral 19, the working surface of which is formed after the usual fashion of graters providing outwardly projecting teeth for 80 grating the nutmeg 11 as the grater is revolving a roughened plate 7 on the follower 4 holding the nutmeg against revolution thereby increasing the efficiency of the grating operation.

At each end the grater 19 is provided with 85 inwardly disposed lugs 20 at right angles to the axis of the grater, said lugs being perforated as shown. A wire 21 is passed lengthwise through the grater and through the perforations of the lugs 20 on one side 90 of the grater while the wire 22 is similarly passed through the perforations of the lugs 20 on the other side of the grater, said wires being bent at right angles to- 95 ward each other immediately outside of the ends of the grater thereby forming spokes 22 for the grater. These wires are twisted together as at 23 in the plane of the axis of the grater to form journals which are seated in the journal bearings of the arms 15 and 16. These wires 21 and 22 are of greater 100 length at one end of the grater than at the other and are twisted together and bent to form an operating crank 24.

A guard 25 extends upwardly and is in- 105 tegral with the upper end of the stem 1.

As will be seen from Figure 1, the stem 1, grater housings 13, 15, 16, and guard 25, are formed in a single integral blank, the side edges of the blank being recessed so that when the edges are brought together these recesses will form the elongated slot 9.

While the blank is being stamped out the nutmeg opening 12 and the elongated slot 8 are simultaneously formed.

In bending the blank to form the stem 1 the arms 13, 15, 16, and guards 25, are brought to the proper relative position which they will occupy in the complete article and in order to hold the blank in this bent position it is only necessary to use the single rivet 18; and to interlock or otherwise suitably secure the side edges of the blank.

The upper end wall of the slot 9 and of the opening 12 are so positioned that the arm 10 becomes engaged therewith and prevents the roughened plate 7 from coming in contact with the teeth of the grater thereby eliminating the possibility of the teeth of the grater from becoming dulled by contact with the roughened plate.

20 As is obvious, my device may be operated by holding the stem in one hand and turning the grater by the crank 24 with the other hand.

I am aware that changes may be made in the details of construction within the spirit of my invention without departing from the scope of the appended claims.

What I claim is:

1. A blank for a nutmeg grater comprising a flat metal plate, arms integral with said plate and extending from one edge and in the plane of said plate; said plate and its arms adapted to be bent to form a housing for a grating mechanism.

2. A blank for a nutmeg grater comprising a flat metal plate, arms integral with said plate and extending from one edge and in the plane of said plate; said plate and its arms adapted to be bent to form a housing for a grating mechanism; a port through said plate terminating in an elongated slot.

3. A blank for a nutmeg grater comprising

ing a flat metal plate having elongated recesses in its side edges, arms integral with said plate and extending from one edge of and in the plane of said plate; a port through said plate terminating in an elongated slot; said plate and its arms being adapted to be bent to form a housing for a grating mechanism.

4. In a nutmeg grater a hollow stem, integral arms extending upwardly from the sides of the stem and bent toward each other and secured together, an arm extending upwardly from the stem at the rear thereof and bent inwardly with its end secured to the other arms to form a housing for a grater, a grater pivotally mounted on the two side arms and within the housing, a follower within the stem adapted to hold a nutmeg against the grater.

5. In a nutmeg grater a hollow stem having a port in one wall thereof; a spring follower slidably mounted in the stem, operating handles secured to the follower, diametrically opposite elongated slots in the walls of the stem in which said handles are adapted to reciprocate, a grater housing on one end of the stem comprising three arms integral with and projecting from the upper edge of the stem with their ends bent inwardly toward each other and secured together, a grater journaled in said housing.

6. In a nutmeg grater, a grater cylinder, a pair of lugs at each end thereof and extending toward the axis of the cylinder, wires connected to each of said lugs and twisted together beyond the ends of the cylinder to constitute a journal, the twisted wires at one end of the cylinder being bent to form a crank.

In testimony whereof I affix my signature.

NORRIS H. PAXSON.
